ANTHONY G. DAVIS AND CHARLES W. BLAKESLEE, OF WATERTOWN, AND EBENEZER B. BEECHER, OF NEW HAVEN, CONNECTICUT.

Letters Patent No. 94,575, dated September 7, 1869.

IMPROVEMENT IN KNITTED STOCKINGS.

The Schedule referred to in these Letters Patent and making part of the same.

To all whom it may concern:

Be it known that we, ANTHONY G. DAVIS and CHARLES W. BLAKESLEE, both of Watertown, Connecticut, and EBENEZER B. BEECHER, of New Haven, in the same State, have invented certain Improvements in the Manufacture of Knitted Stockings; and we do hereby declare that the following, taken in connection with the drawings which accompany and form part of this specification, is a description of our invention sufficient to enable those skilled in the art to practise it.

Our improvements consist in a knitted stocking made complete upon a knitting-machine, so as to be not only seamless, but also with a proper swell or bulge for the heel, as hereinafter described; and also in an improved process of knitting upon machinery a fashioned seamless stocking.

Most, if not all, so-called seamless machine-made stockings, when they leave the machine, are incomplete, and require to have a gap or slit, or other unclosed part, closed up or finished by hand-knitting, crocheting, or otherwise. This gap is sometimes left beneath the foot near the toe, at other times on the upper side of the foot, and sometimes beneath the heel. Where stockings have been made continuously, beginning at the tip of the toe and ending at the top of the stocking, they come from the machine with their last row of knitting unselvaged, and requiring, in order to prevent their ravelling out, to be finished or selvaged by hand.

The heel of a stocking has also been knitted in circular machines having a circular series of fixed needles, by building upon a portion (say half) of the needles a sort of cone or semi-sphere, by first knitting half way around the circle, and then retracing or reversing the knitting over the same set of needles, (omitting one or more, as desired, at the end of every course,) this reversing and shortening of the course making a tapering piece, to which is knitted a similar piece, in inverse order, that is, by reversing and widening the course, the two pieces so united forming a sort of semi-sphere, which being afterward knitted to a foot or leg-piece, forms a heel.

We have successfully produced our stocking upon a machine of that class having two parallel rows of needles, and in which the thread or yarn-carrier is arranged so that it may travel around the machine, or around one end and return, as the character of the work may require; as, for instance, in those patented to us, July 14, 1868, No. 79,897, and August 11, 1868, No. 80,853.

In this machine, we can use parallel rows of needles of the whole length of the series, or use parallel rows at the middle only, (lowering out of action the remainder,) or use any other portion of the rows, and still knit tubular work with unbroken courses, notwith-

standing the thread-carrier may travel some distance from the last needle, on one side, to the first one on the other side, thus enabling us to knit tubes of any desired size in the same machine, and, consequently, stockings of any size required.

This much is premised by way of presenting more clearly hereafter the novel mode in which our heel is made, and which is a consequence of the peculiar feature of adding needles to or taking them from the end of the series used in making the uniform tubular part.

We set up our work in the usual way to make a selvage-edge that will not ravel, upon as many of both rows of needles as will make a tube of the proper size for the top of the stocking, (always commencing at the top,) and we always knit from the top to the toe in order to insure a finished selvage, as aforesaid, at the top, for if we should commence at the toe, the last course of knitting, when taken from the machine, would require all its loops to be taken up.

Supposing the number of needles in each row of the machine to be seventy-five, and that one hundred stitches are needed to form the first course set up for a stocking, then we drop out of the action of the needle-operating cam a number of the needles at both ends of each row, sufficient to leave at the middle portion of each row fifty needles to commence with, the needles so thrown out of action being held as a reserve, to be called into use whenever any widening is required, and not otherwise.

The work being set up, as above, upon the one hundred needles, the machine is set in operation, and a tube is knitted continuously of uniform diameter, or with a swell for the calf, if preferred, until it is desired to narrow below the calf. To effect this, a needle or two at one end only of the rows is thrown out of action, by sliding it down its groove beneath the action of the cam, and the loops of such retired needles being transferred to the next adjacent operative needle, the knitting proceeds as before. Other needles are then similarly retired, and their loops similarly transferred, until the narrowing has been carried to the extent desired, this narrowing, it will be observed, being thus far always made only at one side of the machine, and at that part only which forms the back of the stocking.

The knitting now proceeds regularly on this reduced number of needles, producing uniform tubular goods of reduced size or diameter, until it is necessary to commence the formation of the heel. This part of the process is very peculiar, as will be seen on reference to the drawing accompanying this specification, in which it will be observed, by tracing lengthwise the lines of stitches, that the heel-portion embraced within the part bounded by lines drawn from 1 to 4, 4 to 3, and 3 to 1, is built directly upon and outside of the

outer one of said lines of stitches, and that such portion is composed of a series of independent rows, each successively shorter than its preceding one, until a sufficient swell or bulge has been fabricated. This is accomplished as follows:

To commence the widening, the needles heretofore retired at the right-hand side of the machine, are, one after another, brought again into action, (the circuit of travel of the yarn-carrier being always such as to deliver to any such needles waiting to receive it,) as slowly or as rapidly as may be desired, to give any required protuberance for the heel, but the machine, at this part of the knitting, is not revolved continuously in the same direction, but is turned only about half way around, more or less, first in one direction and then in the other, taking up, as above stated, more needles at the right, and dropping as rapidly as may be desired numbers of needles at the left, thus forming a peculiar gore-like addition, A, to the tube, but differing from a gore in this, that a part of it is built out and projects beyond where any gore proper could be placed, that is, beyond the line of a fabric in which the gore is introduced. This protuberance having been extended outward as far as required, tubular knitting is now resumed, and, narrowing as before, again begins to diminish gradually the protuberance, and preferably this is continued, as shown, from 4 to 6, until fewer needles are left in action than at any other previous stage of tubular knitting, after which continuous tubing, of uniform diameter, is made, until the narrowing for the toe commences, and this narrowing is commenced and continued at both ends of the rows of needles, until the toe is gradually tapered to its tip.

It will be seen, from the above description, that a single yarn may compose the whole stocking, from top

to toe; that neither the top nor any widening nor narrowing part, heel-part, nor toe-part, is left incomplete, and necessitating sewing or seaming; and that if it should be attempted to unravel the stocking, it could be done complete, selvage and all, from end to end, without break, a fact which, it is believed, cannot be asserted of any machine-made selvage-topped stocking ever before made.

It will also be seen that (except at one part of the toe) all the widening and narrowing, and hence the variation from regular, even knitting caused thereby, is done at the back of the stocking, where it is most required, and does not appear at the front or side as a blemish in the goods.

We claim—

1. A stocking having a heel knitted in the manner described.
2. A machine-made seamless stocking, fashioned complete for wear upon the machine, from a continuous yarn, and with a heel made in the manner shown and described.
3. The process herein described of forming the heel of a stocking.
4. The process herein described of knitting a stocking upon a machine employing two straight rows of needles.
